(57) **CLAIM**

The ornamental design for a cleaning brush with a ninety-degree offset handle as shown and described.

DESCRIPTION

FIG. 1 is a top perspective view of a cleaning brush with a ninety-degree offset handle, showing our new design;

FIG. 2 is a left side elevation view thereof;

FIG. 3 is a right side elevation view thereof;

FIG. 4 is an end elevation view shown in the direction from the brush;

FIG. 5 is an opposite end elevation view shown in the direction from the handle;

FIG. 6 is a top plan view thereof;

FIG. 7 is a bottom plan view thereof; and,

FIG. 8 is another perspective view thereof with broken line environment which forms no part of the claimed design. The broken lines depicting a pair of hands and a bottle detail in FIG. 8 show an environment and form no part of the claimed design.

1 Claim, 8 Drawing Sheets
